CLAIM

The ornamental design for an automatic dental floss container, as shown and described.

DESCRIPTION

FIG. 1 is a perspective view of an automatic dental floss container showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent the portions of the design that form no part of the claim.
